UNITED STATES PATENT OFFICE

146,908

DESIGN FOR A CIGARETTE LIGHTER

Raymond J. Goddard and Leonard Dalkoff, Rock Island, Ill., assignors to Aztec Supply Co., Rock Island, Ill., a corporation of Illinois

Application October 27, 1945, Serial No. 123,250

Term of patent 3½ years

(Cl. D48—27)

To all whom it may concern:

Be it known that we Raymond J. Goddard and Leonard Dalkoff, citizens of the United States and residents of Rock Island, in the county of Rock Island and State of Illinois, have invented a new, original, and ornamental Design for a Cigarette Lighter, of which the following is a specification, reference being had to the accompanying drawings, forming part thereof.

Figure 1 is a perspective view;

Figure 2 is a perspective view looking in the opposite direction with parts in different position;

Figure 3 is a front elevation;

Figure 4 is an end elevation;

Figure 5 is a top plan view; and

Figure 6 is a bottom plan view of a cigarette lighter showing our new design.

We claim:

The ornamental design for a cigarette lighter, as shown.

RAYMOND J. GODDARD.
LEONARD DALOFF.
